UNITED STATES PATENT OFFICE.

WILLAMETTE JOAQUIN YOUNG, OF MIAMI, FLORIDA.

SUSPENSORY.

Application filed February 29, 1924. Serial No. 695,984.

To all whom it may concern:

Be it known that I, WILLAMETTE JOAQUIN YOUNG, a citizen of the United States, and a resident of Miami, in the county of Dade and State of Florida, have invented certain new and useful Improvements in Suspensories, of which the following is a specification.

This invention relates to suspensories, and 10 has for its object to provide an article of this character which is so constituted that the sack thereof may be readily renewed and yet is properly supported when in use so as to effectively carry out its intended purposes.

15 Other objects and advantages of the invention reside in certain novel features of the construction, combination and arrangement of parts which will be hereinafter more fully described and particularly pointed out 20 in the appended claims, reference being had to the accompanying drawings forming part of this specification, and in which:

Figure 1 is a perspective view, showing the preferred embodiment of the invention 25 as when in use;

Figure 2 is a perspective view, showing parts disassociated for the sake of illustration; and

Figure 3 is a view in section on line 3—3 30 of Figure 1.

Referring to the drawings it will be seen that in the embodiment of the invention illustrated a supporting belt is provided and includes sections 5 and 6 suitably attached to a supporting member, designated 35 generally at 7. Of course, the sections 5 and 6 are adapted to be connected to each other by buckles or suitable fastening devices.

The supporting member 7 comprises a 40 back piece 8 of fabric and a similar front piece 9, the pieces 8 and 9 being disposed in face to face relation and being secured together along their upper edges by stitching 45. These pieces 8 and 9 are of approximately triangular formation but the portions thereof which would correspond to the apices of the triangles are cut away to form a recess 11 in the supporting member.

A sack designated generally at 12 is 50 provided, and has attaching and supporting tabs 13 integrally formed at the opposite sides of the upper front portion of the sack. These tabs 13 define between them a recess 14 which is complementary to the recess 11 55 of the supporting member, when these parts

are associated whereby the front opening of the suspensor is defined.

The upper ends of the tabs 13 are bound with tape 15 and in the tape 15 button-holes 16 are formed, so that the tabs may be buttoned onto buttons 17 secured to the back pieces 8 of the supporting member 5. After the tabs 13 are thus secured to the supporting member, the front piece 9 thereof is disposed flush up against the back piece and 60 overlies the tabs 13. The buttons 17 also serve to secure the front piece 9 flush up against the back piece 8 and overlying the tabs 13, the buttons 17 coacting with button-holes 18 formed in the front piece 9 in order 65 to accomplish this arrangement. The points 19 of the supporting member are held together by buttons 20 and button-holes 21.

The upper edge of the rear portion of the sack 12 is provided with a binding 22 70 through which a draw string 23 is extended, the draw string being also extended through eyes 24 provided in the back piece 8 of the supporting member and through eyes 25 in the front piece 9 thereof and then being tied, as at 26, in front of the supporting member 75 above the front opening of the suspensor.

It is to be understood that leg straps may 80 be employed if preferred.

With this arrangement the sack 12 may be constructed of comparatively inexpensive fabric and since the sack 12 is detachable and replaceable it may be discarded when desired and replaced by an entirely new sack 90 although of course it may be removed for any purpose. When the sack 12 is associated with its supporting member it is so supported and disposed as to carry out its intended purpose in a proper and efficient 95 manner.

A suspensor of this kind I consider an improvement over those that are in general use for the reason that the sack which could be manufactured for a very low cost, and 100 being detachable, the expense of renewing, and throwing away the one that had been worn until soiled would be less than having same laundried.

I claim:

A suspensor, including a supporting member made up of a front piece, and a back piece permanently secured together along their upper edges, a sack constructed of comparatively inexpensive fabric and be- 110

ing designed to be discarded and renewed when soiled and having tabs, each tab having a binding formed with a button hole, buttons secured to the front face of the back piece, and cooperable with said buttonholes whereby the sack is detachably secured to the supporting member, the front piece having button-holes cooperable with the buttons of the back piece to hold the front piece up

against the back piece and overlying the tabs, the sack and the supporting member having complementary recesses defining the front opening of the suspensory, the recess of the supporting member defining points thereon and fastening devices on the front face of the back piece for holding the points together.

WILLAMETTE JOAQUIN YOUNG.
